CORNCOB BURNER

Walter C. Polk, Fort Branch, Ind.

Application July 13, 1951, Serial No. 236,580

2 Claims. (Cl. 110—18)

1

This invention relates to improvements in forced draft incinerators for waste material, and more particularly to an improved corn cob burner, the primary object of the invention being to provide a more practical and efficient device of this kind which lasts longer than conventional incinerators of this type, is easier and less expensive to operate, substantially eliminates smoke and soot discharge, produces substantially less ash and residue to be cleaned out, and which can be constructed more quickly and with less expense for materials and labor.

Another important object of the invention is to provide an incinerator of the above-indicated character which produces more rapid and complete combustion of the material being incinerated at substantially lower than usual wall temperature through provision for a cooling air blanket indrawn from the outside through wall openings and rising along the interior wall surfaces by reason of the forced draft tuyère grate arrangement provided and by the natural rise of heated air in the interior of the incinerator due to combustion.

A further important object of the invention is to provide a hollow, vertical, open-top, cylindrical incinerator of the character indicated above, wherein the forced draft burner tuyère grate is located at the center of the incinerator, away from the walls thereof, and provision is made for supplying the material to be incinerated to the center of the incinerator immediately above the grate in an arrangement such that the material is burned almost immediately and the burned material is deposited on the floor of the incinerator in an easily removable slag form in a circle around and concentrically spaced from the grate, due to discharge of combustion air by the grate in both upward and lateral directions.

Other important objects and advantageous features of the invention will be apparent from the following description and the accompanying drawings, wherein for present purposes of illustration only, a specific embodiment of the invention is set forth in detail.

In the drawings:

Figure 1 is a side elevation, partly broken away and partly in vertical section, to show interior structure:

Figure 2 is an enlarged, fragmentary, top plan view;

Figure 3 is a fragmentary, horizontal section taken on the line 3—3 of Figure 1;

Figure 4 is a horizontal section taken on the line 4—4 of Figure 1; and

2

Figure 5 is a fragmentary, transverse, vertical section taken on the line 5—5 of Figure 2.

Referring in detail to the drawings, wherein like numerals designate like parts throughout the several views, the illustrated corn cob incinerator comprises a fireproof housing 7, cylindrical in shape, its diameter and height to vary with the burning capacity required, comprising a poured reinforced concrete outer wall 8, a fire brick liner 9, with asbestos mortar insulation 10 between the brick and concrete, and with a screen 11 made of No. 9 galvanized wire in tension covered with small galvanized wire cloth 12 over the top to arrest sparks arising as a result of both natural and forced drafts, and designed principally for the safe and efficient burning of corn cobs at handling and shipping points. The forced draft is applied in the center of the housing 7 at ground line 13 by a blower 14 located outside the housing, through a duct 15 installed below the dirt floor 16 of the housing, exhausting through a cast tuyère grate 17, causing better combustion and more rapid combustion. Air is also drawn by the effects of the natural and forced drafts through vertically spaced rows of holes 18 in the walls, which rises around the interior surfaces of the walls and reduces the temperature against the walls. Cobs to be incinerated are supplied through a declining spout 19 in an opening 20 in the wall arranged to deposit the cobs near the center of the housing and over the tuyère grate 17. At least one of the vertically spaced rows of openings 18 is disposed above the level at which the lower end 35 of the spout enters the housing, and at least one other such row is disposed below this level and between it and the top of the grate 17.

The concrete outer wall 8 is preferably only six inches thick, and the fire brick liner 9 is preferably only four and one-half inches thick, with one-half inch of asbestos mortar 10 between the concrete and brick, making a total wall thickness of eleven inches. This compares with the general practice of having walls 32½ inches thick at the bottom. Some of the advantages of this reduction in wall thickness are lower first cost both of materials and labor, and better radiation of heat, thus reducing the high internal wall temperature which otherwise causes the walls to crack.

The tuyère grate 17 has a series of holes 21 in its horizontal top 22 for vertical discharge of air and is positioned above the floor 16, and has side openings 23 providing for horizontal discharge of air. This delivery of oxygen will cause more perfect and more rapid combustion and also cause

the "hot spot" of the fire to be in the center of the housing away from the walls. This offers these advantages over the present system of burning cobs. The "hot spot" is at the center of the housing, while in the conventional type it occurs at the walls, and this excessive heat at the walls damages them, even getting so hot that it will melt the fire brick. Also the combustion is more nearly perfect, reducing the amount of ashes approximately 90 per cent, and burning these ashes into a hard clinker. This clinker forms around the tuyère grate 17 without touching it, because of the lateral air blast blowing the molten material away from the grate 17. This clinker resembles the crater of a volcano, attaining a thickness of about 12 inches and a diameter of approximately five feet in three full days of burning. It is a very hard, glassy mass, easily broken up for removal. This reduction in ashes is advantageous because the burner does not have to be cleaned of ashes or residue so often, and each day's burning starts with practically a clean burner. The above-described forced draft also makes the combustion more rapid and burns the cobs practically as fast as they are supplied to the incinerator, thus avoiding any large accumulation of cobs in the incinerator. Another benefit of the more nearly perfect combustion thus attained is the elimination of practically all smoke and obnoxious gases which otherwise result from the slow imperfect combustion in the conventional incinerators. This is a very important advantage, especially in cities having smoke ordinances with smoke "spotters" on the job. The blower forcing in a supply of fresh cool air also keeps the tuyère grate at an outside air temperature and prevents it from burning out.

The location of the forced draft in the center of the housing 7, together with the natural heat draft, creates a siphon jet action which draws cool air into the interior of the housing 7 through the holes 18 in the wall. This cool air rises so as to form a "curtain" of cool air near the wall and diminishes the heat on the walls, thus prolonging the life of the housing 7. In the conventional type of incinerators, the hot air from the "hot spots" around the wall rises along the wall and heats it, causing the lining to expand and exert a pressure against the outer wall, causing it to crack and even in some instances bursts the steel bands placed around the housing at different levels.

The insulating liner 19, formed preferably of one-half inch of asbestos mortar, located between the brick liner 9 and the outside concrete wall 8, is provided to insulate the heat from the concrete wall 8, and to provide a cushion for the fire brick liners 9 to expand into, when heated, thereby diminishing the outward pressure on the concrete wall 8.

The preferably 4½-inch thick fire brick liner 9 is formed of bricks laid in a continuous spiral from the bottom to the top, with no mortar in the cross joints, the fire bricks to have only one side dipped in a fluid fire clay mortar at time of placing in the wall. This contrasts with the usual practice of having fire brick liners ranging from 18 inches thick at the base to nine inches thick at the top, with resultant saving in much of the material and labor costs.

In the conventional cob incinerator the air for combustion is drawn through holes in the wall near the bottom. This causes slow combustion at the start and allows excessive quantities of cobs to accumulate in the incinerator, which in time, after burning well, make a very hot fire pro-

ducing an excessive amount of heat in the housing, due to the quantity of cobs burning. Because of the location of these holes, the hottest spots are at the holes where the oxygen supply is greatest. This is a great detriment to the housing, since it applies excessive heat to the walls, causing them to crack, burst and burn out. Also, on account of the poor combustion in this type of burner, excessive amounts of smoke and obnoxious gases are given off, and cross winds blowing through the vent holes above the fire pass out on the opposite side of the burner carrying smoke with them which smokes the walls. In the present invention these faults are eliminated by transferring the "hot spot" to the center of the housing by means of the blower 14, duct 15 and tuyère burner grate 17, using the holes 18 in the walls merely to supply cool air to bathe the walls and keep them cooler. In the drawings only three rows of vent holes are shown which were sufficient to prevent any smoke on the walls of a test apparatus. Due to the upward rush of heat through the center of the housing drawing air in through the vents 18, the outside of the apparatus remains clean.

The screen 11 on top of the housing 7 is formed by stretching No. 9 galvanized wires 25 from pins 26 placed in the top of the concrete wall 8, while it is being poured. These wires 25 are placed off center so as to avoid building up at the center of the housing 7. Also, these wires 25 being on a chord of the circle, the tension on the housing wall is nearer an end pull than a cross pull, avoiding a strain that would be produced by a right angle mesh tension which would cause vertical checks on the outside concrete wall 8. On top of this No. 9 galvanized wire support I lay strips 27 of small mesh galvanized wire cloth 12 to arrest sparks from discharging from the top of the housing. The advantages of this type of screen are ease of installation, lower cost both of materials and labor, and being flush with the top of the housing wall makes all air and heat discharge vertically instead of having part of it subject to horizontal air currents through vertical sections of the screen projecting above the housing, as is the case in most conventional burners. Due to the turbulence of the air caused by the cool air rushing in through the outside vents 18 and the amount of air supplied by the blower 14 blending with the heated air from combustion in the center of the housing, the heat is so reduced when it reaches the screen 11, which is preferably 34 feet above the earth floor 16, that it does not even effect the galvanizing on the wire of the screen 11.

A banked dirt fill 28 is placed on the dirt floor 16 around the lower end of the housing wall, except at the location of the clean-out opening 29 which is provided in the housing wall at ground level. Ventilating and cooling holes 31 surround the opening 29 through which the charging spout 19 enters the housing 7, the inner end of the spout 19 being flush with the interior surface of the housing wall, this arrangement being provided to prevent fire from traveling up the spout 19.

The shelling of 12,000 bushels of corn produces about 82 tons of cobs, which, when dumped into a conventional burner in a day's run, will sometimes fill such burner approximately half full. Since the charge burns at first at the top, the complete burning of the charge runs into the night before a really hot and efficient fire develops, which requires watching. This contrasts with the operation of the present invention,

wherein the cobs are burned almost as quickly as they are charged into the burner and do not accumulate to any great extent in the burner.

What is claimed is:

1. In an incinerator, a vertical cylindrical hollow housing having a substantially plain cylindrical sidewall and being open at its upper end, a bottom wall closing the lower end of said housing, a tuyère grate mounted on and rising above said bottom wall and concentrically spaced from said sidewall, said grate being provided with side openings and with top openings, means connected to said grate for supplying air under pressure to said grate to discharge air laterally toward the housing sidewall at the lower end of the housing and upwardly in the housing, a declining charging spout having a lower end traversing the housing sidewall and entering the interior of the housing adjacent to the lower end of the housing and on a level above said grate, the housing sidewall being provided with a plurality of horizontal rows of circumferentially spaced outside air intake openings, one of said rows of air intake openings being located on a level between the lower end of the charging spout and said grate, and another row of air intake openings being located on a level immediately above the lower end of the charging spout.

2. In an incinerator, a vertical cylindrical hollow housing having a substantially plain cylindrical side wall and being open at its upper end, a bottom wall closing the lower end of said housing, a tuyère grate mounted on and rising above said bottom wall and concentrically spaced from said sidewall, said grate being provided with side openings and with top openings, means connected

to said grate for supplying air under pressure to said grate to discharge air laterally toward the housing sidewall at the lower end of the housing and upwardly in the housing, a declining charging spout having a lower end traversing the housing sidewall and entering the interior of the housing adjacent to the lower end of the housing and on a level above said grate, the housing side wall being provided with a plurality of horizontal rows of circumferentially spaced outside air intake openings, one of said rows of air intake openings being located on a level between the lower end of the charging spout and said grate, and another row of air intake openings being located on a level immediately above the lower end of the charging spout, the sidewall of the housing being otherwise imperforate.
